(57) **CLAIM**

The ornamental design for an electric razor, substantially as shown and described.

DESCRIPTION

FIG. 1 is an isometric view showing the front, top and one side of our invention;

FIG. 2 is a top plan view of our invention;

FIG. 3 is a bottom plan view of our invention;

FIG. 4 is a front elevation view of our invention;

FIG. 5 is a rear elevation view of our invention;

FIG. 6 is an elevation view showing one side of the electric

razor of our invention; and,

FIG. 7 is an elevation view of the other side of the electric

razor of our invention.

The broken lines are shown for illustrative purposes only and form no part of the claimed design.
